CLEANING TOOL NOZZLE AND AGITATOR

Dale C. Gerber, North Canton, Ohio, assignor to
 The Hoover Company, North Canton, Ohio, a
 corporation of Ohio

Application June 10, 1948, Serial No. 32,113

7 Claims. (Cl. 15—373)

1

The present invention relates to suction cleaners and more particularly to surface cleaning tools for use with suction cleaning apparatus.

An object of the invention is to provide a new and improved surface cleaning tool. Another object is to provide a cleaning tool having a movable nozzle lip to selectively provide nozzle mouths of varied cross-sectional area. A further object is to provide a cleaning tool having a brush which is selectively operable with respect to the surface to be cleaned. Another object is to provide a cleaning tool having a brush which is selectively operable by a movable nozzle lip. Other objects and advantages of the invention will be apparent from the following specification and drawings wherein:

Figure 1 is a perspective view showing a cleaning tool connected to a suction cleaner apparatus;

Figure 2 is a fragmentary bottom plan view of one embodiment of the invention;

Figure 3 is a section showing the large nozzle connected to the source of suction, and the brush in inoperative position;

Figure 4 is a section showing the cleaning tool elevated from the surface to be cleaned with the movable nozzle lip in its projected position;

Figure 5 is a section showing the small nozzle mouth connected to the source of suction and the brush in operative position;

Figure 6 is a fragmentary bottom plan view of another embodiment of the invention;

Figure 7 is a section showing the large nozzle mouth connected to the source of suction and the brush in inoperative position;

Figure 8 is a section showing the cleaning tool elevated from the surface to be cleaned with the movable nozzle lip in its projected position; and

Figure 9 is a section showing the small nozzle mouth connected to the source of suction and the brush in operative position.

The embodiment of the invention disclosed in Figures 1 to 5 comprises a suction cleaner of the cylinder type having a casing 10 in which is disposed an unshown filter and a source of suction, and extending from the casing 10 is a flexible hose 11 attached to a rigid wand 12 connected to a cleaning tool 13.

The cleaning tool 13 includes a body 14 having a nozzle mouth 15 defined by a front lip 16, end lips 17—17 and a rear lip 18, the latter forming part of a member 19 mounted on a pair of pins 20—20 each of which is pivotally supported in one of the end lips 17. The nozzle mouth 15 extends substantially the length of the body 14 and communicates with a central air

2

passageway 23 which at its upper end connects with the rigid wand 12 and thus to the source of suction. A suitable swivel joint 24 is provided to rotatably connect the rigid wand 12 to the body 14. A flexible member 25 is connected to the body 14 and to one end 26 of the pivoted member 19 to form part of the air passageway 23, and cooperates with the end lips 17—17 and pivoted member 19 to form a bristle housing chamber 28.

Each of the pins 20 is provided with a crank arm 29 and attached to the latter and the adjacent end lip 17 is a spring 30 disposed about the pin 20. The springs 30 normally urge the member 19 to the position shown in Figure 4 when the cleaning tool is elevated from the surface being cleaned indicated at 32, whereby upon moving the cleaning tool forwardly as it contacts the surface 32, the member 19 assumes the position in Figure 3 to form the nozzle mouth 15 and places it in operative cleaning relation with the surface 32 and also connects it to the source of suction.

Formed in the pivoted member 19 is a nozzle mouth 35 for passage of a high velocity air stream, and it is of less cross-sectional area than the nozzle mouth 15. The small nozzle mouth 35 is placed in operative cleaning position with respect to the surface 32 by elevating the cleaning tool as shown in Figure 4 and then pulling the tool rearwardly as the edge 36 of the member 19 engages the surface 32 to thereby pivot the member 19 to the position shown in Figure 5 to connect the small nozzle mouth 35 with the air passageway 23 and thus the source of suction. When the pivoted member 19 is in the position shown in Figure 5, the edge 36 of the pivoted member 19 seats in a recess 37 and closes the large nozzle mouth 15. The opposite sides of the pivoted member 19 are provided with bearing surfaces 38 and 39 to respectively engage the surface 32 when the large nozzle mouth 15 and small nozzle mouth 35 are in operative position with respect to the surface 32.

At the rear of the cleaning tool body is an elongated recess 40 in which is movably mounted the brush back 41 of a brush 42 having bristles 43. The bristles 43 are urged into engagement with the surface 32 by a plurality of spaced springs 44, only one of which is shown, and projection of the brush 42 is limited by angular members 45—45 abutting the brush back 41. When the brush 42 is in operative position, shown in Figure 5, the bristles 43 are moved into engagement with the surface

32 by rotating the cleaning tool body on the arcuate surfaces 46 formed on the end lips 17. The bristles 43 are inoperative when the pivoted member 19 is in the position shown in Figure 3, in which position the member 19 covers the bristles 43 and also moves the brush inwardly of the recess 40 due to engagement of the member 19 with the surface being cleaned.

In operation, assume the cleaning tool is connected to the source of suction and is elevated from the surface 32 which is to be cleaned, as shown in Figure 4, and it is desired to employ the large nozzle mouth 15 to remove non-imbedded dirt. At this elevated position of the cleaning tool, the springs 30 pivot the member 19 to project the end 36 below the nozzle mouth as shown in Figure 4. The operator places the cleaning tool on the surface 32 with a forward motion to engage the member 19 with the surface 32 and cause it to move to the position shown in Figure 3. In this position the member 19 covers the bristles 43 to render them inoperative and the brush 42 is also moved upwardly into the recess 40 against the force of the springs 44. When the member 19 is so adjusted the large nozzle mouth 15 is defined by the front lip 16, end lips 17-17 and the edge 18 of the member 19, while the flexible member 25 forms part of the air passageway 23. The large nozzle mouth 15 provides for passage of a relatively low velocity air stream to remove dirt from the surface 32.

If the dirt, threads and other litter, is imbedded in the surface 32 the small nozzle 35 is employed. In order to shift the small nozzle mouth 35 into operative position, the cleaning tool is elevated from the surface 32 whereupon the springs 30 pivot the member 19 to the position shown in Figure 4. The operator then lowers the cleaning tool onto the surface 32 with a rearward motion causing the edge 36 of the member 19 to engage the surface 32 and move the member 19 to the position shown in Figure 5 to thereby connect the small nozzle mouth 35 with the source of suction. The small nozzle mouth 35 permits passage of a high velocity air stream to remove the dirt from the surface 32.

When the member 19 is in the position shown in Figure 5, the bristles 43 are uncovered and are urged into operative position by the springs 44. The bristles 43 engage the surface 32 upon rotation of the cleaning tool on the arcuate surfaces 46 of the end lips 17 to thereby loosen the dirt for passage through the small nozzle mouth 35.

The embodiment of the invention disclosed in Figures 6 to 9 comprises a cleaning tool 55 having a nozzle mouth 56 defined by a rear lip 57, end lips 58-58 and a front lip 59 forming one edge of a member 60. The nozzle mouth 56 communicates with an air passageway 61 which at its upper end is rotatably joined with the rigid wand 12 for connection with the source of suction in the casing 10. A flexible member 62 is seated at 63 in the cleaning tool body and has its free end 64 curved for sealing engagement with the member 60 to form part of the air passageway 61.

The member 60 is mounted on pins 65-65 each of which is pivotally supported in one of the end lips 58. Each of the pins 65 is provided with a crank arm 66 and attached to the latter and the adjacent end lip 58 is a spring 67 disposed about the pin 65. The springs 67 normally urge the member 60 to the position shown in Figure 8 when the cleaning tool is lifted from 75

the surface to be cleaned indicated at 69, whereby upon moving the cleaning tool rearwardly as it contacts the surface 69 the member 60 assumes the position shown in Figure 7 to complete the nozzle mouth 56 and connect it to the source of suction.

A nozzle mouth 70 of less cross-section than the nozzle mouth 56 is formed by the rear lip 57, part of the end lips 58-58 and the edge 71 of the member 60 as shown in Figure 9. The small nozzle mouth 70 is placed in operative position by elevating the cleaning tool as shown in Figure 8 and then lowering the tool upon the surface 69 with a forward motion to engage the end 71 of the member 60 with the surface 69 and pivot the member 60 to the position indicated in Figure 9.

The opposite sides of the member 60 are provided with bearing surfaces 73 and 74 to respectively engage the surface 69 when the nozzle mouths 56 and 70 are in operative position. Attached to the member 60 is a member 76 having a serrated edge 77 which cooperates with the edge 71 in defining the front lip of the small nozzle mouth 70. The curved end 64 of the flexible member 62 remains in contact with the pivoted member 60 as the latter is moved to its different position to maintain an air seal therebetween. The end lips 58 are each provided with an arcuate surface 75 to permit tilting of the cleaning tool on the surface 69.

Disposed in an elongated recess 80 is a brush 81 having bristles 82 which are urged into engagement with the surface 69 by a leaf spring 83 as shown in Figure 9. The brush is inoperative when the member 60 is in the position shown in Figure 7, in which position the member 60 covers the bristles 82 and also moves the brush 81 inwardly of the recess 80 due to the surface 73 on the member 60 engaging the surface 69.

In the operation of this embodiment of the invention, the large nozzle mouth 56 is formed by elevating the cleaning tool from the surface 69 to permit the springs 67 to rotate the member 60 to the position shown in Figure 8. The operator then places the cleaning tool on the surface 69 by a rearward motion to pivot the member 60 to the position shown in Figure 7, wherein the edge 59 of the member 60 cooperates with the end lips 58 and rear lip 57 to define the large nozzle mouth 56. In this position the member 60 covers the bristles 82 to render them inoperative and urges the brush 81 into the recess 80 against the force of the spring 83.

When it is desired to clean with the small nozzle mouth 70 and the bristles 82, the cleaning tool is raised from the surface 69 and the operator then applies the cleaning tool to the surface 69 by a forward motion to move the member 60 to the position shown in Figure 9 to thereby define the small nozzle mouth 70. In this position of the member 60 the bristles 82 are exposed and are urged into engagement with the surface 69 by the leaf spring 83 to assist in cleaning the surface 69.

While I have illustrated and described the invention in considerable detail, it is to be understood that various changes may be made in the arrangement, proportion and construction of parts without departing from the spirit of the invention or the scope of the appended claims.

I claim:

1. A surface cleaning tool comprising a body, a nozzle mouth in said body, a surface agitator mounted on said body exteriorly to and inde-

pendent of said nozzle mouth for engagement with the surface to be cleaned, first lip means defining a part of a surface engaging lip for said nozzle mouth, second lip forming means movably mounted on said body independently of said surface agitator for movement to one position to cooperate with said first lip means to define the complete lip of said nozzle, said second lip forming means when in said one position having means to cover said surface agitator to prevent engagement of the latter with the surface to be cleaned.

2. A surface cleaning tool comprising a body, a surface agitator on said body for engagement with a surface to be cleaned, a first nozzle in said body, means movably mounted on said body and having therein a second nozzle mouth, means defining a conduit for connecting said nozzles with a source of suction, and means supporting said movable means on said body for movement to one position to obstruct said first nozzle except for the area of said second nozzle mouth and connect the latter to said conduit and movable to another position with respect to said surface agitator to prevent said surface agitator from engaging the surface to be cleaned.

3. A surface cleaning tool comprising a body, an air passageway in said body for connection with a source of suction, means forming a nozzle mouth connected to said air passageway, a surface agitator, means mounting said agitator in said body independently of and projecting in the same direction as said nozzle mouth for engagement with the surface to be cleaned, and means mounted on said body for movement with respect to said agitator to one position to restrict air flow through said nozzle mouth to said air passageway and movable to another position to prevent engagement of said agitator with the surface to be cleaned.

4. A surface cleaning tool comprising a body, a nozzle in said body for cleaning a surface, an air passageway in said body connecting said nozzle to a source of suction, a surface agitator on said body projecting in the same direction as said nozzle for removable engagement with the surface to be cleaned, means mounted on said body independently of said agitator for movement to one position to uncover said agitator for engagement with the surface to be cleaned and movable to another position to cover said agitator for non-engagement with the surface being cleaned without interrupting flow of air through said nozzle, said means being biased to project beyond the mouth of said nozzle and agitator when said body is lifted from the surface being

cleaned and movable into said different operative positions by engagement with the surface, and maintained in either of its said positions during reciprocation of the body on the surface being cleaned.

5. A surface cleaning tool comprising a body, a nozzle in said body for cleaning a surface, an air passageway in said body connecting said nozzle to a source of suction, a surface agitator mounted on said body projecting in the same direction as said nozzle for removable engagement with the surface being cleaned, means mounted on said body and operatively connected to said agitator and movable independently of said agitator to disengage the latter from the surface being cleaned without interrupting flow of air through said nozzle, said means being biased to project beyond the mouth of said nozzle and agitator when said body is lifted from the surface being cleaned and movable into different operative positions with respect to said independently movable agitator by engagement with the surface being cleaned to control said removable engagement of said agitator with respect to the surface being cleaned, and maintained in either of its positions during reciprocation of the body on the surface being cleaned.

6. A surface cleaning tool as described in claim 3 wherein said last mentioned means include lip forming means positioned to restrict said air flow through said nozzle mouth upon movement of said means to said one position.

7. A surface cleaning tool as described in claim 5 wherein said means include lip forming means for said nozzle when positioned to disengage said agitator from the surface being cleaned.

DALE C. GERBER.
